VEHICLE TIRE

Arthur H. Nellen, Merion Park, Pa., assignor to
Lee Rubber & Tire Corporation, Conshohocken,
Pa., a corporation of New York

Application August 24, 1948, Serial No. 148,273

Term of patent 14 years

(Cl. D90—20)

To all whom it may concern:

Be it known that I, Arthur H. Nellen, a citizen of the United States, and a resident of Merion Park, county of Montgomery, State of Pennsylvania, have invented a new, original, and ornamental Design for a Vehicle Tire, of which the following is a specification, reference being had to the accompanying drawings, forming a part thereof, wherein:

Figure 1 is a perspective view of a vehicle tire showing my new design;

Figure 2 is a transverse sectional view thereof as taken along the line 2—2 of Figure 1; and

Figure 3 is a fragmentary plan view thereof.

The dominant features of my design reside in that portion shown in full lines in the drawing.

I claim:

The ornamental design for a vehicle tire, as shown and described.

ARTHUR H. NELLEN.
